United States Patent Office

Des. 194,026
Patented Nov. 13, 1962

194,026

CANOPY

Harold Baker, Lexington, Ky., assignor to Baker Steel and Engineering Corporation, Lexington, Ky., a corporation of Kentucky

Filed Feb. 23, 1962, Ser. No. 68,933

Term of patent 14 years

(Cl. D13—1)

The dominant features of my design reside in the portion shown in full lines, such portion being characterized by the twisted configuration thereof as best shown in the drawings.

I claim:

The ornamental design for a canopy, substantially as shown and described.
